THREAD GRINDING MACHINE

Stanley Jaffa Harley and John Ernest Wainwright, Coventry, England

Application August 14, 1942, Serial No. 454,862
In Great Britain November 7, 1940

6 Claims.

(Cl. 51—95)

This invention relates to improvements in and in the production of taps, dies and the like screw-threading tools.

In the formation of screw threads by means of taps and dies of the orthodox types the initial operation is much more favourable to the tool than to the work, the conventional tapering of the first tap or die providing a strong thread form towards the leading end designed to make the maximum cut at the core of the work, the amount of cut decreasing progressively as the full thread form enters the work.

In use, however, as is well known, there is a heavy resistance to the initial engagement of the first tap or die owing to the taper, the initial part of the operation having an action resembling that of a reamer and, in the case of a male tool, such as a tap, setting up a bursting stress in the work-piece. Moreover, the form of the cutting teeth at the leading end of a first tap or die of the orthodox type is such as to form a very weak section at the start of the thread which has a tendency to strip and rub.

The primary object of the present invention is to obtain a definite and easier engagement of the tool with the work to be threaded by providing for a better control and distribution of the cutting load and a more favourable ratio of initial section of thread to that of the tool with a proportionate reduction of the present reaming effect.

A further object of the invention is to form screw-threading tools in such a manner that a greater part of the cutting load is taken by the flank or flanks of the thread on the tool with a side cut.

In the method of producing lead on taps, dies and the like screw-threading tools according to the present invention relative axial movement between the rotating fluted blank and the grinding or other thread-forming tool is accelerated or decelerated in predetermined increments between the lands of said blank.

In order to obtain unilateral cutting on the leading flank of the thread by the thread-forming tool, the relative axial movement between the latter and the rotating fluted blank is retarded between the lands in pre-determined increments and for such duration that cutting threads are formed from zero to a completely full form by the action of a multiform tool or wheel and of a controlling mechanism which is pre-set to complete the taper for the required length and then cuts out, after which the said relative movement

continues with an uninterrupted pitch progression.

To obtain unilateral cutting on the following flank of the thread the operation is similar except that in this case the relative movement between the blank and the thread-forming tool is accelerated between the lands.

Bilateral cutting on both flanks is obtained in successive operations by a combination of the two methods above described.

In addition to the method above described the invention includes the provision of means for carrying the same into practical effect, said means operating to advance and/or retard the relative axial movement between the blank and the thread-forming tool to produce a false pitch between the lands of a given length of the blank and to produce a true pitch normal to the tap or die for the remaining length thereof.

In the accompanying drawings,

Figure 1 is a side view of the work-head of a screw-thread grinding machine illustrating one way of carrying out the present invention.

Figure 2 is a similar view of an alternative arrangement.

Figure 3 is a longitudinal section through the improved tap showing progressive increase of leading flank of thread.

Figure 4 is a similar view showing progressive increase of following flank of thread.

Figure 5 is a similar view showing progressive increase on both flanks of thread.

Figure 6 illustrates one of the improved taps.

According to the arrangement shown in Figure 3, 1 in which the work-head 2 of a screw-thread grinding machine carries and rotates the blank or work-piece 21 and is normally traversed across the screw-thread grinding wheel A by means of a lead screw 3 engaging a nut 4 secured to the work-head; the said nut is rotatably mounted in a lug 5 on the work-head and provided with an axial extension carrying a pinion 6. This pinion is rotated to advance or retard the movement of the nut and hence of the work-head relatively to the normal movement produced by the rotation of the lead screw, by means of mechanism including a cam 7 and a ratchet wheel 8 operated from said cam and in geared relation with said pinion 6. The cam is rotated by means of worm gear 9 from a shaft 10 which derives its rotary motion from a motor C through the power input shaft 11 by means of worm gear 12 and drives the rotatable work spindle 13 by means of spur gear 14. The speed of rotation of the cam

is thus correlated with that of the work-piece. The ratchet wheel 8 is given a stepped rotary movement by the cam 7 through the agency of a spring-loaded plunger 15 mounted to slide in a bearing 16 carried by the work-head, the plunger having a roller 17 at one end bearing against the cam and a pivoted pawl 18 at the other end engaging the ratchet wheel. The motion of the ratchet wheel is imparted to the pinion 6 and hence to the nut 4 at the desired ratio by means of a train of change gears 19. The cam is formed and timed so that during the times the flutes of the rotating blank are passing the grinding wheel the axial or traversing movement of the blank across the grinding wheel is retarded in pre-determined increments by the action of the ratchet wheel on the pinion. The duration of retardation is such that cutting threads are formed from zero to a completely full form by the action of a rotating multi-ribbed grinding wheel A shown in dotted lines in Figure 3, the rotating tap blank 21 being traversed in the direction of the arrow. At the stage of the operation shown, the taper portion of the tap has been completed. Thereafter the ratchet mechanism aforesaid is thrown out of action in the manner hereinafter explained, and the remaining part of the blank left parallel, the threads to be formed on this part being indicated in dotted lines at the right-hand of Figure 3. This operation gives a progressive increase on the leading flanks of the thread.

Alternatively, the cam 7 may be formed and timed so that during the times the flutes of the rotating blank are passing the grinding wheel the axial or traversing movement of the blank is accelerated in pre-determined increments in which case the threads are formed from zero to a completely full form with progressive increase on the following flanks, as represented in Figure 4.

Bilateral cutting on both flanks of the thread can be obtained by carrying out the above operations in succession, the result being represented diagrammatically in Figure 5 and by the complete tap in Figure 6.

The duration of the lead control produced by the cam can be controlled in every case by means of a stop 20 adjustably mounted on the ratchet wheel 8 and adapted to throw the pawl 18 out of action when the taper is completed after which the grinding of the thread proceeds in the normal manner with uninterrupted pitch progression.

In the alternative arrangement shown in Figure 2, the blank 21 may be carried by a sub-work-head 22 slidably mounted on the main work-head 2 and the required acceleration or deceleration in the axial traverse of the blank or work-piece 21 produced by means of a cam 7^a in cooperation with a rack 23 and sine bar 24. In this case the cam is driven from the motor C through the power input shaft 11 by worm gear 25 through change gears 26 and the telescopic work-spindle 13 by means of a double worm drive 27, 28. The rack 23, which may be suspended by a cable 29 passing over a pulley 30 and suitably counterbalanced, is given a stepped downward movement by the cam through the agency of a spring-loaded plunger 31 slidably mounted in a bearing 32 and having a roller 33 at one end bearing against the cam 7^a and a pawl 34 at the other end engaging the rack. The sine bar 24, which is formed integral with or fixed to the rack bears against a slipper 35 pivoted to one

end of a push rod 36 slidably mounted in the main work-head 2 and bearing at its other end against the back of the sub-work-head. The return movement of the latter is produced by means of a suitably arranged spring or weight D. The main work-head is operated in the usual manner by the lead screw 3 and a nut and slides upon the bed E or table of the machine. The rack 23 can be prevented from accidental displacement by means of the spring loaded detent 37.

As before, the duration of the acceleration or deceleration in the traversing movement of the blank is controlled by means of a stop 20 adjustably mounted on the rack and adapted to throw the pawl 34 out of action after which the two work-heads move together under the influence of the lead screw with an uninterrupted pitch progression.

By suitable formation of the sine bar irregular increments of acceleration and deceleration may be obtained.

Taps and dies produced according to this invention are distinguished from those of the orthodox type in that the pitch of one or of both flanks of the thread varies by predetermined increments from the leading end. In the case of the following flank the pitch increases from the leading end and in the case of the leading flank the pitch decreases in a similar manner.

We claim:

1. Apparatus for producing lead on taps, dies and the like fluted screw-threaded tools comprising a work-head, a work-spindle rotatably mounted therein, a rotating lead screw for traversing said work-head relatively to a thread-forming tool, a nut rotatably mounted in said work-head and engaging said lead-screw, a cam rotating correlative with said work-spindle, a pawl operated by said cam, a ratchet wheel operated by said pawl, and a train of gears in operative relation between said ratchet wheel and said nut.

2. Apparatus for producing lead on taps, dies and the like fluted screw-threaded tools comprising a main work-head, means for traversing the same relatively to a thread-forming tool, a sub-work-head mounted for sliding movement upon said main work-head, a rotating work-spindle mounted in said sub-work-head, a tail-stock and spindle mounted in said sub-work-head, means for holding said spindles against relative axial movement, and means operating correlative with said work-spindle for moving said sub-work-head relatively to the main work-head in the direction of the traversing motion of the latter between the actual thread forming operations on the lands of a fluted tap or die blank rotating with said work-spindle.

3. Apparatus according to claim 2 in which the means employed for moving the sub-work-head on the main work-head, include a cam rotating correlative with the work-spindle and mechanism actuated thereby and operating to move the sub-work-head in one direction of traverse against the action of means exerting a thrust in the reverse direction.

4. A machine for producing relief in screw-thread taps and dies, said machine comprising a work-head adapted to support and rotate the work-piece, means for traversing said head in a direction parallel with the rotational axis of said work-piece, thread-forming means for producing a screw-thread on the lands of said work-piece, and mechanism for varying the speed of the trav-

ersing motion of said head relatively to the speed of rotation of said work-piece, said mechanism comprising a toothed ratchet element, a cam, a pawl actuated by said cam and actuating said ratchet element, and means for operating said cam.

5. A machine for producing relief in screw-thread taps and dies, said machine comprising a work-head adapted to support and rotate the work-piece, means for traversing said head in a direction parallel with the rotational axis of said work-piece, thread-forming means for producing a screw-thread on the lands of said work-piece, and mechanism for varying the speed of the traversing motion of said head relatively to the speed of rotation of said work-piece, said mechanism comprising a toothed ratchet element, a cam, a pawl actuated by said cam and actuating said ratchet element, means for operating said cam, and a stop adjustably mounted on said toothed

ratchet element and moving with the latter into a position wherein it prevents the actuating engagement of said pawl with said ratchet element.

6. Apparatus for producing lead on taps, dies and the like fluted screw-threading tools comprising a main work-head, means for traversing the same relatively to a thread-forming tool, a sub-work-head mounted upon said main work-head and carrying a rotating work-spindle, a cam rotating correlatively with the work-spindle, a rack and sine bar actuated by said cam and operating to move the sub-work-head in the direction of the traversing motion of the main work-head between actual thread forming operations on the lands of a fluted tap or die blank rotating with said spindle, and means for effecting the return movement thereof.
